(57) **CLAIM**

The ornamental design for a heat protection glove for hand-gripping implements, as shown and described.

DESCRIPTION

FIG. 1 is a perspective view of a heat protection glove for hand-gripping implements showing my new design.

FIG. 2 is a left side elevation view thereof;

FIG. 3 is a right side elevation view thereof;

FIG. 4 is a top-plan view thereof;

FIG. 5 is a bottom-plan view thereof;

FIG. 6 is a front elevation view thereof; and

FIG. 7 is a rear elevation view thereof; and,

FIG. 8 is a top-plan view thereof with the hook and loop fastener for opening and closing the front end of the heat protection glove shown in an open position for accepting implements.

The short-segment broken lines showing a person's arm and hand holding a spatula illustrate the environment in which the claimed design is used and form no part of the claim. The longer-segmented broken lines shown on the surfaces of the claimed design illustrate features of the article to which the design is applied that form no part of the claim.

The crosshatched pattern, although shown intermittently, is meant to represent fabric, and is understood to be distributed uniformly over the surfaces of the claimed design on which the crosshatching resides. The stippling shown in the drawings represents shading.

The claimed heat protection glove for hand gripping implements is used for protecting the hand and arm of a person while hand-gripping an implement near a barbecue, a fire place, a stove or other heat source.
